UNITED STATES PATENT OFFICE.

WILLIAM E. TAYLOR, OF NEW ROE, KENTUCKY.

DESIGN FOR AN INKSTAND.

SPECIFICATION forming part of Design No. 12,290, dated May 31, 1881.

Application filed March 7, 1881. Term of patent 14 years.

To all whom it may concern:

Be it known that I, WM. E. TAYLOR, of New Roe, Allen county, Kentucky, have invented a Design for Inkstands, of which the following is a specification.

In the drawings, the Figures 1 and 2 represent my invention in perspective, and 3 in cross-section at $x x$, Fig. 1.

The invention consists in forming an inkstand with radial points a , and with a stopper, b , the latter arranged at the base of each point, and provided with a ball or knob on the top of each stopper.

Having thus described all that is necessary to a full understanding of my design, what I claim as new is—

A star-shaped inkstand, having at the base of each point a stopper, b , with a ball or knob on its upper end, as shown and described.

WILLIAM ELDEN TAYLOR.
